UNITED STATES PATENT OFFICE.

KNEUD E. LITTLE, OF TAHLÉQUAH, OKLAHOMA.

DRUM-RADIATOR FOR HEATING-STOVES.

1,178,164.

Specification of Letters Patent.

Patented Apr. 4, 1916.

Application filed May 8, 1915. Serial No. 25,435.

To all whom it may concern:

Be it known that I, KNEUD E. LITTLE, a citizen of the United States, residing at Tahlequah, State of Oklahoma, have invented certain new and useful Improvements in Drum-Radiators for Heating-Stoves, of which the following is a specification.

This invention relates to certain improvements in drum radiators for heating stoves and the objects and nature of the invention will be readily understood by those skilled in the art in the light of the following explanation of the accompanying drawings illustrating what I now believe to be the preferred embodiments among other formations, arrangements and constructions within the spirit and scope of my invention.

An object of the invention is to provide improved means for increasing the area of the air heating surfaces of stoves.

A further object is to provide improved means for increasing the circulation of air over the heating surfaces of stoves.

25 A further object is to provide means whereby the heating efficiency of stoves may be materially increased without correspondingly increasing the consumption of fuel.

The invention consists in certain novel 30 features in construction and formation, and in combinations and arrangements as more fully and particularly set forth and pointed out hereinafter.

Referring to the accompanying drawings: 35 Figure 1, is a side elevation of a stove embodying my invention having a portion broken away disclosing a sectional view of my invention. Fig. 2, is a rear elevation. Fig. 3, is a detail bottom plan of the removable top or cover. Fig. 4, is a top plan with the cover removed.

Referring to the particular example illustrated, I somewhat diagrammatically illustrate a heating stove embodying an exterior hollow shell, wall or casing 1, at its upper end provided with a preferably removable top or cover 2, having an outwardly projecting annular flange closing down on the top edge of the casing, and an 45 annular depending flange 4, snugly fitting down within the upper end of the casing. This top is also formed with a central heated air outlet opening 3, and with an off-center smoke outlet opening 5, surrounded by an upwardly extending nipple 6, to receive a smoke pipe (not shown).

Within the casing 1, and above the combustion chamber of the stove, I arrange an air heating drum or chamber 7. This chamber is preferably horizontally arranged and completely spans and closes the space within the casing 1, except for a restricted vertical flue 8, here shown sector shape, formed in this instance between the vertical casing 1, and the straight front edge wall of the chamber 7. The chamber is shown vertically thin or narrow with respect to its horizontal dimensions and is preferably provided with a flat imperforate bottom wall directly above the combustion space and completely closing the upper portion of the interior of the casing except for vertical smoke flue 8. The chamber 7 is also provided with a preferably flat top wall which is imperforate except for a vertical air outlet opening aligned with the opening 3 in the top 2, and surrounded by an annular pipe or cylinder 10, fixed to said top wall of chamber 3, and extending upwardly therefrom through opening 3, to 70 form the hot air discharge outlet from chamber 7, and to form an annular smoke flue or passage 12, around the pipe 10, and within the upper end of the casing 1, and between the top 2, and the top wall of the chamber 7. The smoke flue 8, opens vertically into this horizontal annular flue 12, and the smoke outlet from the flue 12, is provided for by the top opening 5, and nipple 6. The flue 8, usually opens into the 75 front portion of the horizontal annular flue 12 and the discharge or outlet 5, into the rear portion of said flue 12. In other words, the smoke outlet from annular flue 12, is from a portion thereof diametrically opposite the portion into which flue 8, discharges.

The chamber 7, is provided with an air inlet opening at one edge thereof open through the casing 1, to the atmosphere at the exterior thereof. In the example illustrated, the flue 8, is arranged at the front edge of the chamber 7, and the air inlet opening to said chamber is arranged at the rear edge thereof, and said opening is in the form of a horizontally elongated slot 7a that in length is less than the greatest diameter of said chamber, although all features of my invention are not so limited.

In operation, the hot burning gases in the combustion chamber of the stove directly 110 impinge against the bottom wall of the chamber 7 and move forwardly along said

wall and upwardly through the flue 8, into the annular flue 12, and out therefrom through the nipple 6. The front edge wall of the chamber 7, and the top wall thereof, 5 are thus exposed to the hot gases as well as the bottom wall, and the pipe 10, is also exposed to the hot gases. The air in the chamber and the pipe 10, is thereby highly heated and exceedingly rapid circulation of air is 10 thereby set up and maintained through passage 11 in pipe 10, and thereinto from chamber 7, and into chamber 7, through its rear inlet opening.

Where the top 2, is rendered removable, 15 the annular flue 12, is thereby rendered readily accessible so that soot and dust can be easily brushed therefrom and allowed to drop into the stove through flue 8.

I do not wish to limit all features of the 20 invention to any particular form or shape of chambers and passages.

It is evident that various changes, variations and modifications might be resorted to without departing from the spirit and scope 25 of my invention, and hence I do not wish to limit myself to the exact disclosure hereof.

What I claim is:

1. An air heating device comprising a casing having a top, a hot air drum within and 30 spanning said casing except for and providing a restricted vertical smoke flue within the casing at one edge of said drum, the edge of said drum opposite said flue having an air inlet opening from the exterior of 35 said casing, and a vertical hot air offtake pipe from said drum to and opening approximately centrally through said top, an annular smoke flue being thereby formed above said drum and below said top and 40 around said pipe and into which said vertical flue opens, a vertical off center smoke discharge from said annular flue being provided through said top.

2. In a device for the purposes substantially as described, an exterior casing, and 45 an air heating drum transversely arranged within the casing and having an air inlet from the exterior of the casing and a hot air

off-take pipe extending upwardly within the casing from the top of said drum, means 50 being provided a distance above said drum and forming the top wall of a smoke flue within the casing above said drum and around said pipe and having a smoke offtake passage, a vertical restricted smoke flue being provided within the casing and past said drum and to said first mentioned smoke flue, substantially as described.

3. In a device for the purposes substantially as described, a casing, a hot air drum within and traversing said casing and closing the same except for a restricted smoke flue leading from the space below the drum to an annular smoke flue above the drum, said drum having an edge air inlet opening 60 through the casing, a transverse wall arranged a distance above the drum and forming the top wall of said annular smoke flue, a smoke discharge from said annular flue being provided, and a vertical hot air offtake 65 pipe of restricted diameter with respect to the diameter of said drum and extending upwardly from said drum and through said wall and being surrounded by said annular smoke flue.

4. In a heating stove, in combination, an exterior casing, means providing an air heating drum extending completely across and closing the interior of the casing except for a restricted vertical smoke passage, the casing having an air inlet opening into an edge portion of the interior of the drum, a vertical hot air offtake pipe within the casing and from the drum, and means providing a top wall for a smoke flue within the casing 80 above said drum and surrounding said pipe and into which said smoke passage discharges at one side of said pipe, said smoke flue having a smoke outlet from its portion at the opposite side of said pipe.

In testimony whereof I affix my signature in presence of two witnesses.

KNEUD E. LITTLE.
